Application July 22, 1946, Serial No. 685,473

11 Claims. (Cl. 101—228)

1

This invention relates to an improved tensioning mechanism for rotary printing presses and, more particularly, to a tensioning mechanism for use in connection with an offset press for printing impressions at spaced intervals on a continuous moving web.

Among the several objects of the invention may be noted the provision of an improved tensioning mechanism adapted to maintain proper tension on a web of material being fed through a rotary offset printing press wherein brand impressions are printed on the web at spaced intervals corresponding to certain lengths; the provision of a tensioning mechanism of this class permitting operation of the press so as to print a wide range of said lengths; and the provision of a tensioning mechanism of this class adapted to permit printing of lengths shorter than, equal to, or longer than the circumference of the plate cylinders or printing rolls of the press. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a diagrammatic side elevation of a rotary offset printing press embodying the improved tensioning mechanism of this invention;

Fig. 2 is an enlarged partial side elevation of the press with the tensioning mechanism set to permit printing of bag lengths shorter than the circumference of the plate cylinders;

Fig. 3 is an enlarged partial side elevation of the press with the tensioning mechanism set to permit printing of bag lengths longer than the circumference of the plate cylinders;

Fig. 4 is an enlarged end view of the web-feeding device for the press, as viewed from line 4—4 in Fig. 1;

Fig. 5 is a right side elevation of Fig. 4;

Fig. 6 is a view partly in section on line 6—6 of Fig. 2;

Fig. 7 is a section taken on line 7—7 of Fig. 2; and,

Fig. 8 is a section taken on line 8—8 of Fig. 3. Similar reference characters indicate corresponding parts throughout the several views of the drawings.

This invention constitutes an improvement

2

over the tensioning mechanism for printing presses disclosed in the Belcher Patent No. 1,978,073. The tensioning mechanism disclosed in this patent is adapted only to permit operation of the press to print bag lengths which are shorter than or, at most, equal to the circumference of the plate cylinders or printing rolls designated 7 in the Belcher patent. The web to be printed is fed by web-feed rolls between an impression cylinder and a printing cylinder. This occurs at a linear speed less than the peripheral speed of the cylinders. The web is intermittently gripped between a raised printing surface on the impression cylinder and the printing cylinder and fed forward at the higher peripheral speed of the cylinders. To compensate for the difference in web speeds, a tensioning mechanism is provided for supplying additional web to the cylinders and for taking up the slack issuing during such operation. The tensioning mechanism is adapted for operation only when the linear speed of the web, as determined by the speed of the web-feed rolls, is less than the peripheral speed of the impression and printing cylinders. This limits the press of the Belcher patent to printing bag lengths shorter than or, at most, equal to the circumference of the plate cylinders.

The present invention extends the range of the press to include the printing not only of lengths which are shorter than or equal to the circumference of the plate cylinders but also to include the printing of lengths longer than the circumference of the plate cylinders. As illustrated in Fig. 1 herein, the tensioning mechanism of the present invention is employed in connection with a rotary offset printing press including a main frame 11 wherein are journaled an impression or blanket cylinder 13, plate cylinders or printing rolls 15, and a printing cylinder 17. The plate cylinders, as is conventional, receive supplies of ink from suitable inking rollers (not shown), and transfer an ink impression of a brand to a raised blanket or printing surface 19 on the impression cylinder 13. The impression cylinder 13 and the printing cylinder 17 have the same surface speeds. The raised surface 19 is adapted to engage the printing cylinder 17 to grip the web W to be printed therebetween. When the web is thus gripped it is positively fed forward at the peripheral speed of the cylinders 13 and 17. At the same time, the ink impression is transferred from the raised surface 19 to the web.

Unprinted web is supplied to the press from

a supply roll 21 supported in roll holder 23. The web is positively fed from the supply roll to the press by a web-feed roll 25, being guided around and pressed against this feed roll by presser rolls 27. Printed web is fed from the press to a suitable winder (not shown) by a web-feed roll 29, being guided around this roll by guide rolls 31. The web-feed rolls 25 and 29 are of the same diameter and are connected by a chain and sprocket drive, as indicated at 33, to rotate at the same speed (Figs. 4 and 5).

The press cylinders and the web-feed rolls are driven from a drive shaft 35 journaled in the feed roll frame. This shaft is driven through a belt and pulley drive from a motor (not shown). The shaft 35 has a pulley 37 on one end for the belts 39 of this drive. On the same end of the shaft is a sprocket 41 of a sprocket and chain drive, generally designated 43, for driving the press cylinders. On the other end of the shaft 35 is a gear 45 which drives the web-feed roll 25 through a change gear drive, generally designated 47. By means of the change gear drive, the web-feed rolls 25 and 29 may be driven to feed the web at a speed either slower, equal to, or faster than the surface speeds of the impression or printing cylinders 13 and 17.

The improved tension mechanism of this invention is supported in a frame 55 disposed between the web-feeding means 25-29 and the main press frame 11. The tensioning mechanism includes two tension rolls 57 and 59 journaled in an oscillating tension frame generally designated 61. Frame 61 comprises a pair of arms 63 centrally connected by a tubular member 65. The arms are secured in alignment on the respective ends of the connecting member by being bolted to flanges 67 welded on the connecting member. The tension rolls 57 and 59 are rotatably supported at the opposite ends of the arms by anti-friction bearings 69 mounted upon studs 71 secured in the ends of the arms. The frame 61 is pivotally supported for oscillation in frame 55 on pivot studs 73 extending from the frame 55 into the ends of the tubular connecting member 65. Anti-friction bearings 75 are provided between the studs 73 and tubular member 65. The tension rolls 57 and 59 and the arms 63 are preferably made of light weight material such as an aluminum alloy.

Idler guide rollers 77 and 79 journaled in the frame 55 cooperate with the upper tension roll 57 to form a loop 81 in the web between the web-feed roll 25 and the press cylinders. Web issuing from the loop is guided by the idler 79 between the impression and printing cylinders 13 and 17. The tension of the web in the loop 81 tends to bias the tension roll 57 to the right and to pivot the tension frame 61 clockwise (Figs. 1, 2 and 3). Idler guide rolls 83 and 85 cooperate with the lower tension roll 59 to form a second loop 87 in the web between the press cylinders and the printed web-feed rolls 29. The tension of the web in the loop 87 tends to bias the tension roll 59 to the right and to pivot the tension frame 61 counterclockwise.

As illustrated in Fig. 2, the tension frame 61 is biased to pivot counterclockwise by spring devices, generally designated 91, connected to the frame at opposite sides thereof. There are two spring devices 91 and each includes a chain 93 removably fastened at one end 95 to the upper side of a collar 97. The two collars 97 are secured to the arms 63 by the bolts which connect the arms and flanges 67. The chains 93 are

guided around rollers 99 and their other ends are connected to tension springs 101, as indicated at 103. Chains 105 are connected to the other ends of the springs, as indicated at 107. Each chain 105 is attached to a take-up pulley 109 on a shaft 111 which may be rotated and locked in an adjusted position by a pawl and ratchet device 113 for adjustably tensioning the springs 101. Ends 95 of chains 93 may be detached from the upper sides of collars 97 and secured to the lower sides of the collars, as indicated at 115 in Fig. 3, so that the spring devices 91 bias the tension frame 61 to pivot clockwise, for a purpose to be mentioned.

When the ends 95 of the chains 93 are attached to the upper sides of the collars 97, as shown in Fig. 2, the tension frame 61 is biased counterclockwise by the spring devices 91 toward the solid-line position wherein the lower portions of the arms 63 engage stops 117. These stops are formed on the ends of the arms 119 of bell-crank levers fixed on a rock shaft 121. The other arms 123 of the bell-crank levers are disposed between spaced fixed stops 125 and 127. These stops limit the oscillation of rock shaft 121 and stops 117 thereon. Stops 117 function to limit pivotal movement of tension frame 61 in counterclockwise direction, as viewed in Fig. 2. The lower ends of the arms 63 of the tension frame engage the stops 117 and rock the shaft 121 until bell-crank arms 123 engage the lower fixed stop 127. Stops 117 also function as kickers to kick the lower ends of arms 63 to the left in a manner to be described. The stops 117 are preferably provided with suitable yieldable elements 129, of rubber or the like, to cushion the impact.

Clockwise pivotal movement of the tension frame 61 from the solid-line position of Fig. 2 is limited by bumpers 131 adjustably mounted on the inside of the side members at the top of frame 55. As illustrated more particularly in Fig. 7, each bumper comprises a bracket 133 having spaced bearing members 135 and 137 thereon. A bumper rod 139 having a cushioned bumper head 141 is disposed for sliding movement in the bearing members. A compression spring 143 reacting between the bearing member 135 and a collar 145 on the bumper rod biases the rod and head 141 toward the tension frame. The collar limits the sliding movement of the bumper rod.

Each side member of frame 55 has an arcuate slot 147 therein. Arcuate racks 149 (not shown in the diagrammatic Fig. 1) are secured on the outside of the side frame members adjacent the slots. Each bumper bracket 133 has a pair of studs 151 and 153 thereon extending through the corresponding slot 147. A hand wheel 155 having a pinion 157 meshing with rack 149 is rotatably mounted on stud 151 on the outside of the side frame members. The hand wheel and pinion are removably retained on the stud 151 by a nut 159 threaded on the outer end of the stud. The bracket 133 is clamped in adjusted position on the side frame member by a nut 161 threaded on the end of stud 153 extending through the slot 147 into engagement with the side frame member. Adjustment of the bumper may be effected even while the press is running by loosening nut 161 and rotating the hand wheel 155 and pinion 157, then tightening nut 161 to clamp the bumper bracket in place. The bumpers may be entirely removed

from the side frame members by removing nuts 159 and 161 and the hand wheel and pinion.

As illustrated in Fig. 3, the tension frame 61 is biased by the spring devices 91 to rotate clockwise to the solid-line position of this figure, wherein the lower portions of the arms 63 engage stops 167. These stops are formed on the ends of the arms 169 of bell-crank levers fixed on a rock shaft 171 parallel to and spaced from the rock shaft 121. The other arms 173 of these bell-crank levers are disposed between an upper fixed stop 175 and a lower resilient stop 177. These stops limit the oscillation of rock shaft 171 and stop 167 thereon. Stops 167 function to limit pivotal movement of tension frame 61 in clockwise direction, as viewed in Fig. 3. The lower ends of arms 63 of the tension frame engage the stops 167 and rock the shaft 171 until bell-crank arms 173 engage the lower resilient stop 177. Stops 167 also function as kickers to kick the lower ends of arms 63 to the right in a manner to be described. The stops 167 are preferably provided with suitable yieldable elements 179, of rubber or the like, to cushion the impact of arms 63.

The lower stops 177 are resilient to absorb the shock of bell-crank arms 173 in the event of breakage of the web. If the web should break when the tension frame is, for example, in the dotted-line position of Fig. 3, the spring devices 91 would rapidly pivot the tension frame 61 clockwise and the lower ends of arms 63 would strike the stops 167 with impact. This impact would be transferred through the bell-crank lever to the lower stop. As shown more particularly in Fig. 8, the lower resilient stop 177 comprises a bumper rod 181 having a bumper head 183 at the upper end thereof. The bumper rod is slidably disposed in a bracket 185. A compression spring 187 reacting between one end of the bracket and a collar 189 on the bumper rod biases the bumper head 183 to a normal stop position. The spring 187 is sufficiently strong so that the bumper head 183 is substantially immovable under ordinary impact of the bell-crank arm 173 thereon.

When the spring devices 91 are connected to the lower sides of the collars 97 to bias the tension frame 61 clockwise, bumpers 131 are removed from the position shown in Fig. 2 and mounted upon the side members of frame 55 in the adjusted position indicated in Fig. 3 to limit pivotal counterclockwise movement of the tension frame. In effecting this transfer, the bumper on the right-hand side of the frame is transferred to the left-hand side of the frame and, similarly, the bumper on the left-hand side of the frame is transferred to the right-hand side.

Means is provided for selectively operating either of the two sets of stops 117 and 167 in timed relation to the printing operation as kickers, dependent upon whether the tension frame is biased to pivot counterclockwise (Fig. 2) or clockwise (Fig. 3). This means includes a rock shaft 201 parallel to and intermediate the rock shafts 121 and 171. Rock shaft 201 is braked by a conventional band brake 203 at one end thereof. Shaft 201 is periodically rocked by a cam-operated linkage from a cam 205 on the impression cylinder 13. The linkage includes a link 207 pivoted at 209 on the main press frame 11. This link has a cam follower 211 adapted periodically to be engaged by cam 205 to pivot the link upward. A bell-crank lever 213

is pivoted on the frame 11 below the impression cylinder. A guide 215 is formed at the end of one of the arms of the bell crank. A connecting rod 217 pivoted at 219 to the link 207 extends through the guide 215. Compression spring 220, reacting between the guide 215 and a nut 221 threaded on the end of the connecting rod, provides a lost-motion connection between the connecting rod and the bell crank. A connecting rod 223 links the other arm of the bell crank and an arm 225 secured to the rock shaft 201.

The cam 205 is phased to lift the cam follower 211 just before the instant when the raised blanket surface 19 on the impression cylinder 13 engages the printing cylinder 11 to feed the web therebetween at the peripheral speed of the cylinders. This actuates the cam-operated linkage quickly to rotate the rock shaft 201 counterclockwise, as viewed in Figs. 2 and 3. When the cam 205 rotates out of engagement with the follower 211, the cam-operated linkage returns to its original position and the rock shaft 201 is thereby rotated clockwise back to its original position.

25 A bell-crank lever having arms 227 and 229 is fixed on the end of rock shaft 201. As illustrated in Fig. 2, the arm 227 is linked to an arm 231 on rock shaft 121 by a connecting rod 233. With this setup of the tension mechanism no connection is established between the rock shaft 201 and the rock shaft 171. As illustrated in Fig. 3, arm 229 of the bell crank may be connected to an arm 235 on the rock shaft 171 by a removable pin 237 extending through an elongate slot 239 in arm 229. With this setup of the tension mechanism, there is no connection between the bell-crank arm 227 and the arm 231 on rock shaft 121. With the connecting rod 233 linking the arms 227 and 231, as illustrated in 35 Fig. 2, the aforementioned rapid counterclockwise rotation of the rock shaft 201 effects a corresponding rapid counterclockwise rotation of the stops 117 on rock shaft 121. Such rotation of the stops 117 effects the striking of a sharp blow upon the lower ends of the arms 63 and kicks them to the left, as viewed in Fig. 2. With the arm 229 of the bell crank pinned to the arm 235 of rock shaft 171, as illustrated in Fig. 3, the rapid counterclockwise rotation of rock shaft 50 201 effects a rapid clockwise rotation of rock shaft 171. This causes the stops 167 on the rock shaft 171 to kick the lower ends of the arms 63 to the right, as viewed in Fig. 3. With either of the above setups, the brake 203 for the rock shaft 201 functions temporarily to retain the shaft 201 at the limit of its counterclockwise rotation to prevent a rebound of oscillating tension frame 61 as it completes a cycle.

Brakes 241 are provided frictionally to retain 60 the tension frame 61 in the solid-line position of Fig. 3 when the spring devices 91 are connected to bias the frame clockwise. These brakes are provided to prevent the tension frame 61 from being pivoted counterclockwise away from the initial position against stops 167 by the tension of the web in loop 87 acting on tension roll 55. Each brake comprises a detent 243 pivoted on the frame 55, as indicated at 245. Each detent has a friction-surfaced detent notch 246 65 wherein the lower end of an arm 63 is adapted to engage. The detents are biased by adjustably tensioned springs 247 into engagement with the lower ends of the arms. Springs 247 are connected between the ends of the arms 249 on the detents and threaded rods 251. Rods 251 extend

through guides 253 on the frame 55. The tension of springs 247 may be varied by adjusting nuts 255 threaded on the ends of the rods. Pivotal movement of the detents is limited by adjustable limit screws 257 threaded through the frame 55 into engagement with arms 259 on the detent. Limit screws 257 may be adjusted to move the detent 243 completely out of engagement with the lower ends of arms 63, as in Fig. 2.

Operation is as follows:

For printing lengths shorter than the circumference of the plate cylinders 15, the elements of the tension mechanism are connected and adjusted as illustrated in Fig. 2. The chains 93 of the spring devices 91 are connected to the upper sides of collars 97, so that the tension frame 61 is normally biased counterclockwise by the spring devices, to the solid-line position of Fig. 2 wherein the lower ends of arms 63 engage stops 117. Bumpers 131 are adjusted in slot 147 to permit tension frame 61 to pivot clockwise from its normal position against stops 117 an amount determined by the arcuate length of the raised printing surface 19 on the impression cylinder 17. This adjustment is such that the upper ends of arms 63 of the tension frame 61 engage the bumpers 131 when the trailing edge of the raised printing surface 19 moves out of feeding contact with the web between the impression and printing cylinders. Rod 233 is connected between arms 227 and 231 on rock shafts 201 and 121, respectively. The pin 237 is removed so that there is no connection between rock shafts 201 and 121. Limiting screws 257 are adjusted to move detents 243 to a position wherein they cannot engage arms 63. The change gear drive for the web-feed rolls 25 and 29 has appropriate change gears connected therein for driving the feed rolls at a peripheral speed less than the surface speeds of the impression and printing cylinders.

During a part of each revolution or cycle of the impression cylinder 13, the web is gripped between and fed forward by the raised printing surface 19 thereon and the printing cylinder 17, and the ink impression is transferred from the surface 19 to the web. The web is positively fed forward during this intermittent printing interval at the surface speeds of the cylinders 13 and 17. During the remainder of each cycle of the impression cylinder 13, the web slips between the cylinders 13 and 17 at the lower speed of travel imparted thereto by the web-feed rolls 25 and 29. The length of web fed forward at the higher speed during the printing interval is determined by the arcuate length of the raised printing surface 19.

When the leading edge of the raised printing surface 19 engages the web at the beginning of the printing interval, the web is accelerated and moved faster than it is supplied by the web-feed roll 25 to the cylinders 13 and 17. Just before this occurs, however, the cam 205 engages follower 211 to actuate the cam-operated linkage 207, 217, 213 etc., rapidly to rotate the rock shaft 201 counterclockwise. Such rotation of rock shaft 201 is transmitted to rock shaft 121 through the linkage comprising arm 227, rod 233 and arm 231 rapidly to rotate shaft 121 counterclockwise. Upon rotation of shaft 121, stops 117 are rapidly rotated to kick the lower ends of arms 63 to the left and thus to pivot tension frame 61 clockwise. This relieves the tension in the web in loop 81 substantially at the instant when the web is accelerated so as to prevent undue tensioning of the web between web-feed roll 25 and cylinders 13 and 17. Immediately thereafter the loop 81

tightens around the upper tension roll 57, and the increased tension in the loop caused by the differential in the peripheral speeds of web-feed roll 25 and cylinders 13 and 17 swings tension frame 61 clockwise until it engages bumpers 131. This engagement occurs when the trailing edge of the raised printing surface 19 moves out of contact with the web. During such clockwise pivoting of the tension frame 61, the spring devices 91 are tensioned. When the trailing edge of raised printing surface 19 moves out of contact with the web at the end of the printing interval, the web is decelerated, the tension of the web in loop 81 decreases, and the tensioned spring devices 91 pivot the tension frame 61 back to its normal position against stops 117.

During the printing interval, the web is fed forward by the impression and printing cylinders faster than it is fed by the printed web-feed roll 29. The accumulating slack between the cylinders and feed roll 29 is taken up in the loop 87 which is enlarged as the lower tension roll 59 moves to the left upon clockwise pivoting of frame 61. This maintains proper tension in the web between the cylinders and feed roll 29. When the web decelerates at the end of the printing interval, the tension frame pivots counterclockwise back to its normal position and the original size of loop 87 is restored.

For printing lengths equal to the circumference of the plate cylinders 15, the elements of the tension mechanism may remain in the connected and adjusted positions indicated in Fig. 2, except that link 233 is removed so that there is no kicking action. The change gear drive for the web-feed rolls 25 and 29, however, is varied to drive the feed rolls at surface speeds equal to the surface speeds of impression and printing cylinders 13 and 17. This is done by substituting the appropriate change gears therein. This results in the speed of the web feed being equal to the peripheral speed of the cylinders and consequently there is no acceleration of the speed of the web during the printing interval. The tension frame therefore remains stationary and the web is fed through the press at constant uniform speed.

For printing bag lengths longer than the circumference of the plate cylinders, the elements of the tension mechanism are connected and adjusted as illustrated in Fig. 3. The chains 93 of the spring devices 91 are connected to the lower sides of the collars 97 so that the tension frame 61 is normally biased clockwise by the spring devices to the solid-line position of Fig. 3 wherein the lower ends of the arms 63 engage stops 167. Bumpers 131 are placed at the other ends of the slots 147, with respect to their Fig. 2 position. The bumpers are positioned to permit tension frame 61 to pivot counterclockwise from its normal position against stops 167 an amount determined by the arcuate length of the raised printing surface 19 on the impression cylinder 17. This position is such that the upper ends of arms 63 engage the bumpers 131 when the trailing edge of the raised printing surface 19 moves out of feeding contact with the web. Pin 237 is inserted through the slot 239 in arm 229 and fastened to arm 235 to connect rock shafts 201 and 121. Rod 233 is removed so that there is no connection between rock shafts 201 and 121. Limiting screws 257 are adjusted to permit springs 247 to raise detents 243 to a position wherein they frictionally latch the tension frame 61 in the solid-line position of Fig. 3. The change gear

drive for the web-feed rolls has appropriate change gears connected therein for driving the web-feed rolls at a peripheral speed higher than the peripheral speed of the impression and printing cylinders.

During the printing interval, the web is gripped between and fed forward by the raised printing surface 19 on the impression cylinder and the printing cylinder at the peripheral speed of these cylinders. This speed is lower than the normal web speed as determined by the web-feed rolls 25 and 29. During the remainder of a cycle of the impression cylinder, the web slips between the cylinders 13 and 17 at the higher normal web speed. The length of web fed forward at the lower speed during the printing interval is determined by the arcuate length of the raised printing surface 19.

When the leading edge of the raised printing surface 19 engages the web at the beginning of the printing interval, the web is decelerated and moved by the cylinders 13 and 17 slower than it is supplied thereto by web-feed roll 25 and slower than it is pulled therefrom by web-feed roll 29. Just before this occurs, however, the cam 205 engages follower 211 to actuate the cam-operated linkage 207, 211, 213, etc., to rotate the rock shaft 201 rapidly counterclockwise. Such rotation of rock shaft 201 is transmitted to rock shaft 171 through arm 229, pin 237 and arm 235 to rotate rock shaft 171 rapidly clockwise. Upon such rotation of shaft 171, stops 167 are rapidly rotated clockwise to kick the lower ends of arms 63 to the right out of the detent notches 246 and thus to pivot tension frame 61 counterclockwise. This relieves the tension in the web in loop 87 substantially at the instant when the web is decelerated, so as to prevent undue tensioning of the web between cylinders 13 and 17 and web-feed roll 29. Immediately thereafter, the loop 87 tightens around the lower tension roll 59 and the increased tension in the loop caused by the differential in the peripheral speeds of cylinders 13 and 17 and feed roll 29 swings tension frame 61 counterclockwise until it engages bumpers 131. This engagement occurs when the trailing edge of the raised printing surface 19 moves out of contact with the web. During such counterclockwise pivoting of the tension frame 61, the spring devices 91 are tensioned. When the trailing edge of the raised printing surface 19 moves out of engagement with the web at the end of the printing interval, the web is accelerated, the tension of the web in loop 87 decreases, and the tensioned spring devices pivot the tension frame 61 back to its normal position against stops 167 with the lower ends of arm 63 engaged in detent notches 246.

During the printing interval, the web is fed forward faster by feed roll 25 than it is taken up by the cylinders 13 and 17. The slack accumulating between the feed roll 25 and cylinders 13 and 17 is taken up in the loop 81 which enlarges as the upper tension roll 57 moves to the left upon counterclockwise pivoting of frame 61. This maintains proper tension in the web between the feed roll 25 and the cylinders. When the web accelerates at the end of the printing interval, the tension frame pivots clockwise back to its normal position and the original size of loop 81 is restored.

Thus, the tension mechanism is readily selectively operable for the printing of lengths either shorter, equal to, or longer than the circumference of the plate cylinders. When the tension

mechanism is set for printing lengths shorter than this circumference (Fig. 2), the upper tension roll 57 functions as a guide to form the loop 81 in the web from which slack is supplied to the impression and printing cylinders during the printing interval. The lower tension roll 59 functions as a guide to form the loop 87 in the web to take up slack between these cylinders and the printed web-feed roll 29. When the tension mechanism is set for printing bag lengths longer than the circumference of the plate cylinders (Fig. 3), these functions are reversed. The upper tension roll 57 forms loop 81 to take up slack in the web between unprinted web-feed roll 25 and cylinders 13 and 17, this slack resulting because roll 25 is feeding the web forward faster than it is being fed by the cylinders. The lower tension roll 59 forms loop 87 to supply slack to the printed web-feed roll 29.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A tension mechanism for rotary printing presses comprising a tension frame having a tension roll in each end thereof, said frame being pivoted for oscillation about an axis intermediate said tension rolls, said frame being swingable about said axis in one direction to one initial position against one stop or in the opposite direction to another initial position against another stop, a spring biasing device detachably connected to the frame for biasing said frame to one of said initial positions, said device being alternatively connectable to said frame for biasing it to the other of said initial positions, a friction brake device adapted frictionally to retain said frame in one of said positions when it is biased to that position, and mechanism whereby said brake device may be held out of engagement with said frame when it is biased into the other of said positions.

2. A tension mechanism for rotary printing presses comprising a tension frame having a tension roll in each end thereof, said frame being pivoted for oscillation about an axis intermediate said tension rolls, said frame being swingable about said axis in one direction to one initial position against one stop or in the opposite direction to another initial position against another stop, biasing mechanism for selectively biasing said frame to one or the other of said initial positions, said stops being movable, and mechanism for selectively actuating said stops to kick the frame away from the stop against which it is biased.

3. A tension mechanism for rotary printing presses comprising a tension frame having a tension roll in each end thereof, said frame being pivoted for oscillation about an axis intermediate said tension rolls, said frame being swingable about said axis in one direction to one initial position against one stop or in the opposite direction to another initial position against another stop, biasing mechanism for selectively biasing said frame to one or the other of said initial positions, said stops being movable, mechanism for selectively actuating said stops to kick the frame away from the stop against which it is biased, and spaced stops for limiting movement of said mov-

able stops, one of said spaced stops comprising a bumper to cushion impact of a movable stop against it.

4. A tension mechanism for rotary printing presses comprising a tension frame having a tension roll in each end thereof, said frame being pivoted for oscillation about an axis intermediate said tension rolls, said frame being swingable about said axis in one direction to one initial position against one stop or in the opposite direction to another initial position against another stop, biasing mechanism for selectively biasing said frame to one or the other of said initial positions, bumpers for selectively limiting oscillation of said frame in one direction from one of said initial positions or for limiting oscillation of said frame in the other direction from the other initial position, said stops being movable, mechanism for selectively actuating said stops to kick the frame away from the stop against which it is biased, and a detent for frictionally retaining said frame in one of said initial positions.

5. A rotary printing press having impression and printing cylinders adapted intermittently to print a web fed therebetween, means for feeding said web between said cylinders at a predetermined speed, a tensioning mechanism for tensioning the web entering and leaving said cylinders comprising a pair of conjointly movable web guides for guiding the web to form a first loop in the web entering the cylinders and to form a second loop in the web leaving the cylinders, a pair of stops spaced in the path of movement of the tensioning mechanism and engageable thereby, one of said stops determining a first initial position of the guides wherein said first loop is extended and from which said guides are movable in one direction to supply slack from said first loop to said cylinders and to take up slack in said second loop, the other stop determining a second initial position of the guides wherein said second loop is extended and from which said guides are movable in the opposite direction to take up slack in the first loop and to supply slack from said second loop to said web feed means, biasing mechanism alternately connectable to said tensioning mechanism for selectively yieldingly biasing said guides toward one or the other of said stops, said stops being movable, and mechanism operating in timed relation with the cylinders for selectively actuating said stops substantially at the beginning of a printing operation to move the tensioning mechanism away from the stop with which it is engaged to relieve the web of undue tension at the beginning of the printing operation.

6. A rotary printing press having impression and printing cylinders adapted intermittently to print a web fed therebetween, means for feeding said web between said cylinders at a predetermined speed, a tensioning mechanism for tensioning the web entering and leaving said cylinders comprising a pair of conjointly movable web guides for guiding the web to form a first loop in the web entering the cylinders and to form a second loop in the web leaving the cylinders, a pair of stops spaced in the path of movement of the tensioning mechanism and engageable thereby, one of said stops determining a first initial position of the guides wherein said first loop is extended and from which said guides are movable in one direction to supply slack from said first loop to said cylinders and to take up slack in said second loop, the other stop determining a second initial position of the guides wherein said second

loop is extended and from which said guides are movable in the opposite direction to take up slack in the first loop and to supply slack from said second loop to said web feed means, biasing mechanism alternately connectable to said tensioning mechanism for selectively yieldingly biasing said guides toward one or the other of said stops, said stops being movable, and mechanism operating in timed relation with the cylinders for selectively actuating said stops substantially at the beginning of a printing operation to move the tensioning mechanism away from the stop with which it is engaged to relieve the web of undue tension at the beginning of the printing operation, said stop-actuating mechanism comprising a cam rotary with the impression cylinder, and a linkage operable by the cam substantially at the beginning of the printing operation, said linkage being selectively connectable to actuate one or the other of said stops.

7. A rotary printing press having impression and printing cylinders adapted intermittently to print a web fed therebetween, means for feeding said web between said cylinders at a predetermined speed, a tensioning mechanism for tensioning the web entering and leaving said cylinders comprising a pair of conjointly movable web guides for guiding the web to form a first loop in the web entering the cylinders and to form a second loop in the web leaving the cylinders, a pair of stops spaced in the path of movement of the tensioning mechanism and engageable thereby, one of said stops determining a first initial position of the guides wherein said first loop is extended and from which said guides are movable in one direction to supply slack from said first loop to said cylinders and to take up slack in said second loop, the other stop determining a second initial position of the guides wherein said second loop is extended and from which said guides are movable in the opposite direction to take up slack in the first loop and to supply slack from said second loop to said web feed means, biasing mechanism alternately connectable to said tensioning mechanism for selectively yieldingly biasing said guides toward one or the other of said stops, a friction brake device engageable with the tensioning mechanism for frictionally retaining the guides in their said second initial position, and mechanism whereby said brake device may be held out of engagement with the tensioning mechanism when the biasing mechanism is connected to bias the guides toward their said first initial position.

8. A rotary printing press having impression and printing cylinders adapted intermittently to print a web fed therebetween, means for feeding said web between said cylinders at a predetermined speed, a tensioning mechanism for tensioning the web entering and leaving said cylinders comprising a pivoted tension frame having tension rolls therein for guiding the web to form a first loop in the web entering the cylinders and to form a second loop in the web leaving the cylinders, a pair of stops spaced in the path of swinging movement of the frame and engageable thereby, one of said stops determining a first initial position of the frame wherein said first loop is extended and from which the frame is swingable in one direction to supply slack from said first loop to said cylinders and to take up slack in said second loop, the other stop determining a second initial position of the frame wherein said second loop is extended and from which the frame is swingable in the opposite di-

rection to take up slack in said first loop and to supply slack from said second loop, biasing mechanism detachably connected to said frame for yieldingly biasing it toward one of said stops, said biasing mechanism being alternatively connectable to said frame for yieldingly biasing it toward the other stop, said stops being movable, and mechanism operating in timed relation with the cylinders for selectively actuating said stops substantially at the beginning of a printing operation to move the frame away from the stop with which it is engaged, to relieve the web of undue tension at the beginning of the printing operation.

9. A rotary printing press having impression and printing cylinders adapted intermittently to print a web fed therebetween, means for feeding said web between said cylinders at a predetermined speed, a tensioning mechanism for tensioning the web entering and leaving said cylinders comprising a pivoted tension frame having tension rolls therein for guiding the web to form a first loop in the web entering the cylinders and to form a second loop in the web leaving the cylinders, a pair of stops spaced in the path of swinging movement of the frame and engageable thereby, one of said stops determining a first initial position of the frame wherein said first loop is extended and from which the frame is swingable in one direction to supply slack from said first loop to said cylinders and to take up slack in said second loop, the other stop determining a second initial position of the frame wherein said second loop is extended and from which the frame is swingable in the opposite direction to take up slack in said first loop and to supply slack from said second loop, biasing mechanism detachably connected to said frame for yieldingly biasing it toward one of said stops, said biasing mechanism being alternatively connectable to said frame for yieldingly biasing it toward the other stop, said stops being movable, and mechanism operating in timed relation with the cylinders for selectively actuating said stops substantially at the beginning of a printing operation to move the frame away from the stop with which it is engaged to relieve the web of undue tension at the beginning of the printing operation, said stop-actuating mechanism comprising a cam on the impression cylinder and a linkage operable by the cam substantially at the beginning of the printing operation, said linkage being selectively connectable to actuate one or the other of said stops.

10. A rotary printing press having impression and printing cylinders adapted intermittently to print a web fed therebetween, means for feeding said web between said cylinders at a predetermined speed, a tensioning mechanism for tensioning the web entering and leaving said cylinders comprising a pivoted tension frame having tension rolls therein for guiding the web to form a first loop in the web entering the cylinders and to form a second loop in the web leaving the cylinders, a pair of stops spaced in the path of swinging movement of the frame and engageable

thereby, one of said stops determining a first initial position of the frame wherein said first loop is extended and from which the frame is swingable in one direction to supply slack from said first loop to said cylinders and to take up slack in said second loop, the other stop determining a second initial position of the frame wherein said second loop is extended and from which the frame is swingable in the opposite direction to take up slack in said first loop and to supply slack from said second loop, biasing mechanism detachably connected to said frame for yieldingly biasing it toward one of said stops, said biasing mechanism being alternatively connectable to said frame for yieldingly biasing it toward the other stop, and a detent engageable with the tensioning mechanism for frictionally retaining the frame in its said second initial position.

11. A rotary printing press having impression and printing cylinders adapted intermittently to print a web fed therebetween, means for feeding said web between said cylinders at a predetermined speed, a tensioning mechanism for tensioning the web entering and leaving said cylinders comprising a pivoted tension frame having tension rolls therein for guiding the web to form a first loop in the web entering the cylinders and to form a second loop in the web leaving the cylinders, a pair of stops spaced in the path of swinging movement of the frame and engageable thereby, one of said stops determining a first initial position of the frame wherein said first loop is extended and from which the frame is swingable in one direction to supply slack from said first loop to said cylinders and to take up slack in said second loop, the other stop determining a second initial position of the frame wherein said second loop is extended and from which the frame is swingable in the opposite direction to take up slack in said first loop and to supply slack from said second loop, biasing mechanism detachably connected to said frame for yieldingly biasing it toward one of said stops, said biasing mechanism being alternatively connectable to said frame for yieldingly biasing it toward the other stop, a friction brake device engageable with the tensioning mechanism for frictionally retaining the frame in its said second initial position, and mechanism whereby said brake device may be held out of engagement with the tensioning mechanism when the biasing mechanism is connected to bias the frame toward its said first initial position.
